UNITED STATES PATENT OFFICE.

JOSEPH L. WALKER, OF BATON ROUGE, LOUISIANA, ASSIGNOR TO K-D BARREL AND HAMPER CO., OF BATON ROUGE, LOUISIANA.

BARREL OR DRUM CONSTRUCTION.

Application filed June 11, 1921. Serial No. 476,855.

To all whom it may concern:

Be it known that I, JOSEPH L. WALKER, a citizen of the United States, residing at Baton Rouge, in the parish of East Baton Rouge and State of Louisiana, have invented a new and useful Barrel or Drum Construction, of which the following is a specification.

This invention relates to a barrel or drum construction and more especially to devices of this character formed of veneer.

It is an object of the present invention to so construct the staves of the barrel or drum or the strips forming the heads thereof or both the staves and the head strips that they will yieldingly press together at their points of connection at all times so as to provide sealed joints which insure proper retention of any materials such as flour, sugar or the like that may be contained in the barrel or drum.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

35 Figure 1 is an end elevation showing several of the numbers of the drum or barrel separated prior to being assembled.

Figure 2 is a similar view showing them assembled.

40 Figure 3 is a view showing the said members assembled to produce a rounded body such as that produced by the staves of a barrel or drum.

45 Referring to the figures by characters of reference 1 designates strips of veneer and each strip has its opposed edges beveled in opposite directions as indicated at 2, the outwardly converging faces provided by these beveled edges being preferably concaved slightly as shown. If the strips are to be assembled for the purpose of forming a barrel head or the like they are left flat and placed in lapped relation as shown in Figure 1. The lapping portions are then 50 pressed together and the strips secured to

cross members 3 by means of brass 4 or in any other suitable manner. By thus pressing together the strips of veneer the outer portion of each lap shown in Figures 1 and 2 will be pressed upwardly by the inner portion of the lap, this outward bending resulting in the binding of the lapping portions tightly together, the outer portion of the lap being slightly curved so as to conform with the curvature of the inner portion of the lap as shown in Figure 2. Consequently a tight joint is provided between the strips 1 and as there is always a pressure between the strips at the points where they lap, it will be obvious that leakage of material between the strips at these points will be prevented. The staves of a barrel or the like can be similarly constructed and such staves have been shown at 5 in Figure 3. These staves are constructed similarly to 75 the strips 1, it being understood that one longitudinal edge of each stave will be pressed outwardly by the adjoining edge of the adjacent stave so that the parts will lap and press together constantly as shown at 80 6 in Figure 3, all of the staves being suitably secured to one or more hoops 7.

Obviously by providing a container with its parts constructed and assembled as set forth, tight joints are insured and the container will thus be capable of holding all kinds of material without danger of waste.

What is claimed is:—

1. A container including strips of veneer each having its outer face beveled along opposed longitudinal edges, said bevels being concaved, the concaved bevel along one edge of each strip lapping and contacting with the inner face of the next adjoining strip.

2. In a container a plurality of strips of veneer or the like, said strips having their outer faces beveled along opposed edges to provide outwardly converging faces slightly concaved, the beveled portions of the strips being disposed in lapped relation, and means for holding the strips flush with one beveled portion of each strip flexed and held by a beveled portion of the next adjoining strip thereby to provide constant pressure between the lapping portions of the strips.

3. In a barrel or similar container a plurality of strips of veneer or the like having their outer faces beveled along opposed edges and said beveled portions being slightly concaved, the beveled portions of

the strips being disposed in lapped relation, and means for fastening the strips together with their corresponding faces substantially flush thereby to hold one beveled portion of each strip constantly pressed against and held flexed by a beveled portion of the next adjoining strip, to seal the joint between the strips.

4. A veneer container comprising separate strips each having its outer face beveled along opposed edges, said bevels being concaved transversely, the said strips being assembled in lapped relation with one concave beveled portion of each strip in contact

with the inner surface of one edge portion 15 of the next adjoining strip thereby to hold said edge portion flexed substantially to conform with the contour of the concaved beveled portion engaged thereby, and means for holding the strips together.

20 In testimony that I claim the foregoing as my own, I have hereto affixed my signature in the presence of two witnesses.

JOSEPH L. WALKER.
